UNITED STATES PATENT OFFICE.

CHARLES E. FLAGG, OF BROOKLINE, MASSACHUSETTS, ASSIGNOR TO CUBICLE STORES, INC., OF BOSTON, MASSACHUSETTS, A CORPORATION OF MASSACHUSETTS.

DESIGN FOR A VENDING CABINET.

Application filed November 9, 1923. Serial No. 7,731. Term of patent 3½ years.

To all whom it may concern:

Be it known that I, CHARLES E. FLAGG, a citizen of the United States, residing at Brookline, in the county of Norfolk and Commonwealth of Massachusetts, have invented a new, original, and ornamental Design for Vending Cabinet, of which the following is a specification, reference being had to the accompanying drawing, forming part thereof.

Fig. 1 is a general approximate fragmentary perspective, and

Fig. 2 is an end elevation of the same.

I claim:

The ornamental design for a vending cabinet, as shown.

CHARLES E. FLAGG.
